CIRCULAR SWING

Wendell Phillips Stampfli, Monahans, Tex.

Application October 15, 1936, Serial No. 105,833
Renewed August 3, 1938

2 Claims. (Cl. 74—522.5)

The invention relates to pull rod swings and more especially to a circular swing.

The primary object of the invention is the provision of a swing of this character, wherein pull rods will operate at an angle and all side sweep is eliminated which generally causes breakage of the pull rods and a straight pull forward and backward is assured, the swing being adaptable for pumping machinery for oil or water wells.

10 Another object of the invention is the provision of a swing of this character, wherein a short length of flexible wire is employed so that shocks and vibration will be absorbed during the working of the pull rods and also enables the working 15 of the said rods at varying angles.

A further object of the invention is the provision of a swing of this character, wherein but a single bearing is required and elimination of side sweep in the rod lines is assured.

20 A still further object of the invention is the provision of a swing of this character, which is simple in construction, thoroughly reliable and effective in its operation, strong, durable, and inexpensive to manufacture and install.

25 With these and other objects in view, the invention consists in the features of construction, combination and arrangement of parts as will be hereinafter more fully described, illustrated in the accompanying drawing, which discloses the 30 preferred embodiment of the invention and pointed out in the claims hereunto appended.

In the accompanying drawing:

Figure 1 is a top plan view of pull rod lines showing the swings constructed in accordance 35 with the invention associated therewith.

Figure 2 is a top plan view of one of the swings.

Figure 3 is a side elevation of one of the swings.

Figure 4 is an end elevation.

40 Figure 5 is an opposite end elevation.

Similar reference characters indicate corresponding parts throughout the several views in the drawing.

Referring to the drawing in detail, A designates 45 generally a series of pull rods, these in the arrangement are disposed at different angles with respect to each other and are operated from a power house B. At the adjacent ends of the rods A are cross pieces 10 and 11, respectively, the 50 rods being anchored therein in any suitable manner preferably through a swivel connection and to these pieces are fitted flexible loops 12 and 13, respectively, the cross head 10 being of less length than the head 11. The loops 12 and 13 by reason 55 of the points of connection thereof with said cross

heads will have the loop 12 of less width than the loop 13. The loops 12 and 13 are reversely trained over a swing and in this instance one being indicated at 14 and the other at 15, respectively. Each swing 14 and 15 is formed with a central bearing 16 from which project arms which may be termed radial spokes 17 supporting a circular pull member 18, the outer periphery of this member being provided with seating grooves 19 for the reversely disposed loops 12 and 13. The pull member of each swing 14 and 15 is provided with notches 20 forming continuations of the channels or grooves 19 so that a closed outer end 21 of each loop can be saddled at the end of the said member and seated in 15 the notch 20 therefor, in conformity with the reversed disposition of the loops when trained over the member and engaged in the channels or grooves 19, the side stretches of the loops being received in these grooves. The swings 14 and 15 allow angular disposition of the rods A with respect to each other and at the same time avoid any possibility of side sweep which results in the breakage of the pull rods and at the same time assures a straight pull forward and 25 backward of such rods when in operation.

The flexible loops 12 and 13 function to absorb shocks and vibrations during the working of the pull rods.

Each swing 14 and 15 at the bearing 16 thereof is journaled on a stud arbor 22 suitably supported to properly locate the swing in the rigging of the pull rods A, the latter being operated from the power unit B.

It should be apparent from Figures 1 and 2 35 of the drawing that there is but one central bearing for each swing 14 and 15 thus there is eliminated the usual bearings as is common in the standard types of swings now employed in pumping machinery for oil or water wells.

The rods in the arrangement thereof in the rigging for pumping machinery or the like can be disposed at any angle up to one hundred and eighty degrees and the circular portion or member of each swing gives a straight pull back and 45 forth eliminating side sweep and minimizing vibration, which in turn causes pull rods to break as with the angular types of swings now in use. The loops engaged on the circular members of the swings serve to deaden vibration and such 50 swing automatically adjusts itself when put into operation, particularly on installation requiring a lesser degree of angular set up than originally ordered and an angular arrangement of the rods at one hundred and eighty degrees or less in the 55

rigging will assure perfect working under the installation.

What is claimed is:

- 5 1. A swing structure fashioned with a spider formed with an arcuate member at the outer end thereof provided with a pair of circumferentially extending grooves terminating in the connecting cable retaining channel formed in an outer end face thereof and embracing a similar pair of coextending grooves terminating in a like channel formed in the opposite face thereof, pull rods, and flexible loops coupled with said pull rods and reversely trained over said arcuate member 10 and saddled in said channels.
- 10 2. A device of the character described com-

prising, a swing structure fashioned with a spider formed with an arcuate member at the outer end thereof provided with a pair of circumferentially extending grooves terminating in the connecting cable retaining channel formed in an outer end face thereof and embracing a similar pair of coextending grooves terminating in a like channel formed in the opposite face thereof, pull rods, and flexible loops coupled with said pull rods and reversely trained over said arcuate member 10 and saddled in said channels.

WENDELL PHILLIPS STAMPFLI.
